UNITED STATES PATENT OFFICE.

JAMES H. HEROY AND WILLIAM W. HEROY, OF NEW YORK, N. Y.

MACHINE FOR GRINDING AND BEVELING PLATE-GLASS.

SPECIFICATION forming part of Letters Patent No. 394,980, dated December 25, 1888.

Application filed January 12, 1888. Serial No. 260,509. (No model.)

To all whom it may concern:

Be it known that we, JAMES H. HEROY and WILLIAM W. HEROY, residing at New York, in the county of New York and State of New 5 York, have invented certain new and useful Improvements in Machines for Grinding and Beveling Plate-Glass, of which the following is a specification, reference being had therein to the accompanying drawings.

10 This invention relates to machines for grinding and beveling plate-glass and similar plates having practically plane surfaces.

The object of the invention is to produce a machine in which the work of grinding and 15 beveling glass plates can be done continuously and with little attention, and in which the plates can be beveled to any usual angle.

The invention consists in the combination of parts by which a continuous reciprocation 20 of the grinding-wheel is produced; also, in the combination of mechanism for holding the plates and adjusting them at a suitable angle to the grinder; also, in the mechanism by which the grinder is supplied with abras- 25 ent material while in use; also, in various details of construction and combinations of elements hereinafter explained.

In the drawings, Figure 1 is a plan of the machine, omitting the plate-table and clamp, 30 the standards which support said table being shown in section. Fig. 2 is a side elevation of the machine, showing the plate-table and plate-clamping devices. Fig. 3 is a vertical cross-section on line $x-x$, Fig. 1, some parts 35 being omitted. Fig. 4 is a detail of the pinions connecting shaft 17 to the counter-shaft. Fig. 5 is a detail of one of the stops.

The numeral 1 indicates the frame of the machine. This frame is somewhat similar to 40 the bench of a metal-turning lathe, and has parallel tracks or bars 2 2, on which the grinder-truck is supported and reciprocates.

The truck 3 is held to the tracks 2 2 by dovetail guide-pieces 4 4, which extend par- 45 allel with the said tracks. The truck 3 is caused to reciprocate longitudinally of the tracks by means of the threaded shaft 5, journaled in the frame and engaging a nut, 6, at- tached to the truck. The shaft 5 carries two 50 fixed pulleys, as 7 and 8, and two idlers, as 9 and 10. Of course the position of these pul- leys may be varied.

The belts 11 and 12 are adapted to drive the fixed pulleys, but run in reverse directions. A double belt-shifter, 13, engages these belts, 55 so as to throw one of them into engagement with a fast pulley and the other with an idler. The belt-shifter 13 is supported by a rod, 14, which is supported on ways in the frame in such manner that it may slide in the direction 60 of its length.

The reverse end of rod 14 is loosely pivoted to a lever, 15, which is pivoted to the frame and bears a fork or belt-shifter, 16. The entire reversing mechanism may be termed an 65 "automatic shifter." A polygonal or splined shaft, 17, is journaled on the frame, extending from end to end parallel with the tracks. This shaft bears a pinion, 18, provided with flanges and free to move lengthwise on the 70 shaft 17, but not to turn independently of said shaft. The shaft 17 has also a fast pulley and a loose pulley. (Shown at 19 and 20.) The truck 3 bears a short counter-shaft, 21, 75 suitably supported in journal-boxes on the truck, and having a fixed pinion, 22, which engages the teeth of pinion 18, before referred to, but rests between the flanges of said pinion, so as to cause pinion 18 to move lengthwise on its shaft when the truck moves 80 lengthwise of the tracks.

The counter-shaft 21, which must rotate with shaft 17, (by means of the intermeshing pinions 18 and 22,) has a bevel-gear, 23, which engages a bevel-gear, 24, on the grinder- 85 shaft 25. The shaft 25 is supported in suitable journal-boxes on the truck 3, so as to be held against motion in the direction of its length, and carries the grinding-wheel 26 and a wheel, 27, which serves to balance said 90 grinding-wheel.

The truck 3 carries two prongs or project- 95 ing pieces, in position to engage stops 31 32 on the shifting bar 14. The stops 31 32 are held on the shifting bar by set-screws or in other convenient manner, and may be adjusted to any position on said bar. Then as the truck 3 is moved to engage one of the pieces with the stop 31 the bar 14 will be moved, the belt-shifter 13 will shift belts 11 100 and 12, so as to reverse the movement of screw 5, and thus run back the truck, and at the same time belt-shifter 16 will shift its belt from pulley 20 to pulley 19, thus stopping

or starting shaft 17, as is requisite. Reverse movement takes place when the other piece engages stop 32.

The grinding-wheel 26 runs in trough 30, which carries sand, emery, or other abrading material suitable to the work. The plane or side faces of wheel 26 are made to carry this material into contact with the plate. The trough 30 is supported on legs or pillars. A shield, 51, extends down from the front of the frame to protect the working parts from sand, &c. Other moving parts are covered or shielded by thin metallic plates as far as possible.

Two standards, 33 33, are pivoted on a rod, 34, near the foot of the frame. At the upper ends of these standards there is a rod, 35, extending from one to the other. A rectangular frame or table, 36, is pivoted to this rod, and presents a plane face or frame toward the working-face of wheel 26. A spring, 37, at each end of the machine and bearing against the standard presses the lower edge of the frame or table 36 toward the grinding-wheel 26, and hooks 38, pivoted to the table and engaging brackets 39 on the standards, steady and support the table. Stops 40, secured on these hooks by set-screws, hold the hooks in proper position with relation to the standards 33.

A shaft, 42, is journaled at each end in the standards 33 and extends through slots 41 in the frame. The shaft 42 bears bevel-pinions 43, which engage a rack, 44, on the frame. The rack 44 and pinion 43 are duplicated, one rack and pinion being placed at each end of the frame.

The shaft 42 may be rotated by a lever or wrench and held in any adjusted position by a clamp or other known mechanism. The engagement of pinions 43 with racks 44 will serve to keep the standards parallel with each other. The standards can thus be swung to any angle (within their limit of movement) around their pivots 34, and the table 36 can be swung on pivot 35 to present its lower edge close to the wheel 26. The bars 46 46 run lengthwise of table or frame 36 and are secured thereto by set-screws. Cross-bars 47 47 hold the ends of the glass plate, which is indicated at 50, Figs. 2 and 3. The bars 47 may be notched and held to bars 46 by screws or in other suitable manner.

The shaft 25 may be set at a very slight deviation from a right angle across the face of truck 3. This will cause the grinding to be done at one side of the shaft, while the other side remains free from the glass plate.

The machine having been constructed as described and shown, or in equivalent manner, the glass is affixed to the frame or table and the machine set in motion. The truck 3 will travel lengthwise of the machine and carry

the grinder with it, the grinder or "mill" 26 running with its lower edge in the sand-trough 30 and having its face in contact with the lower edge of the glass at an angle thereto. The truck having traveled until it shifts the bar 14 and having ground a "cut" off the surface of the glass will be reversed and move in the opposite direction until the shifting bar is again moved, when the first operation will be repeated. The springs 37 serve to hold the glass up to the wheel, but will give to prevent breakage.

What we claim is—

1. In a glass-grinding machine, a track, a reciprocating truck traveling lengthwise thereof, a grinding-wheel carried by said truck, a shifter connected to said truck to reverse the movement thereof automatically, a trough beneath the grinding-wheel and extending along the path of movement thereof, and a table adjustable relatively to the grinding-wheel, all in combination, substantially as described.

2. In a glass-beveling machine, a supporting frame-work, a traveling grinding-wheel thereon, standards pivoted near the bottom of the frame and extending above the top thereof, a table pivoted to said standards above the grinding-wheel, and a spring pressing one edge of said table toward the wheel, all in combination, substantially as described.

3. A pair of standards pivoted to the frame, a table pivoted near the upper end of these standards, springs pressing the lower end of the table away from the standards, a hook-adjustable stop arranged, substantially as described, to limit the swing of the table, and a rotating grinder in proximity to the edge of the table, all in combination, substantially as described.

4. A pair of standards pivoted to the frame, a shaft carried by said standards, pinions on the shaft engaging racks on the frame, and a table pivoted to said standards, all combined in a glass-beveling machine, substantially as described.

5. In a plate-glass-beveling machine, the combination of a grinding-wheel, adjunctive mechanism, substantially as described, for rotating and reciprocating said wheel, a shield in proximity to the wheel and covering the driving-gear thereof, an elongated fixed trough in which said wheel travels, and a pivoted table for supporting the glass, the parts being relatively arranged substantially as described.

In testimony whereof we affix our signatures in presence of two witnesses.

JAMES H. HEROY.
WILLIAM W. HEROY.
